HINGE CONNECTION

Alfred Boenecke, Berlin, Germany

Application May 24, 1938, Serial No. 209,795
In Germany June 3, 1937

5 Claims. (Cl. 16—171)

My invention relates to hinge connections.

It is an object of my invention to provide an improved hinge connection, or hinge, which lends itself to quantity production of some suitable plastic material, such as artificial resin, by a process of molding under pressure.

To this end, I provide a hinge member defining a bearing which is open at one side. In the constructional example which will first be described, this hinge member is subdivided into a pair of spaced-apart bearing members whose bearings are open at the lower side, and the two members are made integral with the rear wall of a box from whose ends they project inwardly. Between the inner ends of the two bearing members, I insert a mating hinge member which is integral with the lid of the box. The mating member is solid and has two pins projecting from its ends which are arranged to enter the open bearings from below. A locking member is connected to the hinge member which defines the bearing. In the said constructional example, the locking member is a portion of the rear wall whose sides are separated from the body of the wall by slots so that the locking member is a sort of tongue which is connected to the body of the wall at its root only and therefore possesses a certain degree of elasticity. The locking member is urged toward the interior of the box by the mating member as the pin, or pins, on the mating member is moved into the open bearing, or bearings, and locks the mating member by elastic reaction when its pin, or pins, is in the bearing, or bearings.

In the accompanying drawing, a box equipped with my hinge connection, and an independent hinge, are illustrated by way of example.

In the drawing

Fig. 1 is a perspective illustration of the complete box, with its lid closed, viewed from its rear wall.

Figs. 2 and 3 are sections, respectively, on the lines II—II and III—III in Fig. 1.

Fig. 4 is a plan view of the box, with its lid removed.

Fig. 5 is a plan view of the lid.

Fig. 6 is a vertical section of the hinge structure, drawn to a larger scale, showing the method of assembly.

Fig. 7 is a transverse section of the independent hinge.

Referring to Figs. 1 to 6 of the drawing, U is a box body and D is the lid which is provided with a solid cylindrical hinge projection 12 integral with the rear wall 11 of the lid D and

moulded with pins 13 and 14 projecting from its ends, the free ends of the said pins being rounded as shown in Fig. 5. The rear wall 15 of the box U is provided with a pair of mating hinge members 16 and 17 which are integral with the said rear wall 15 and are adapted to receive the hinge projection 12 between them. The hinge members 16, 17 are provided with slots or recesses 18 in their inner end walls, the said slots being open at their lower ends (Figs. 2 and 6) and are adapted to receive the pins 13 and 14, the slots and pins being axially aligned so as to enable the lid D to swing about the axis of the pins 13, 14. The hinge members 16, 17 and the cylindrical hinge projection 12 form together a substantially continuous cylinder when the lid is in position on the box.

The lid is maintained in position on the box body by means of an elastic locking member 21 integral with the rear wall 15 of the box body, the said locking member comprising a resilient tongue formed by providing slots 19, 20 in the said rear wall in proximity to the centre of the space between the inner ends of the hinge members 16, 17, so that the member 21 is connected to the wall 15 at its base only, as indicated by the horizontal dotted line in Figs. 2 and 6. The tongue 21 is sufficiently resilient to enable it to be forced inwardly towards the interior of the box body. The rear wall 15 of the box body is provided with a recess 15' extending between the inner ends of the hinge members 16, 17, the bottom of said recess being substantially tangential with the cylindrical surfaces of the said hinge members, as shown in Fig. 4, the upper part of the tongue 21 being correspondingly thinned so that its rear face is substantially level with the bottom of the recess 15'. The recess 15' extends downwardly from the upper edge of the rear wall 15 of the box body for a sufficient distance to allow the hinge projection 12 to pass below the hinge members 16 and 17 and to be moved upwardly to bring the pins 13, 14 into engagement with the recesses 18.

A projection 21' is provided on the rear face of the tongue 21, the said projection having bevelled edges and being provided at its upper end with a cylindrical seating curved to the radius of the cylindrical hinge projection 12 as shown in Fig. 6. In the normal upright position of the tongue 21, the projection 21' projects beyond the bottom of the recess 15' as shown in Fig. 4.

When it is desired to place the lid D in position on the box body, the hinge projection 12 is inserted into the recess 15' until it bears against

the projection 21' and the tongue is forced inwardly into the box body in the direction of the horizontal arrow (Fig. 6) until the rear face of the projection 21' is level with the bottom of the recess 15', whereupon the hinge projection is moved upwardly in the recess 15' in the direction of the vertical arrow shown in Fig. 6. On the pins 13, 14 arriving at their final upper position in the recesses 18, the tongue 21 snaps back into its normal position with the cylindrical seating at the upper end of the projection 21' below the hinge projection 12, thereby retaining the hinge projection in position with its pins 13, 14 in engagement with the slots 18.

15 Referring now to Fig. 7, this hinge is equipped with plates 22 and 23, with holes 24 and 25, respectively, for attaching it to the lower part and the lid of a box, or to any other objects to be hinged together. Otherwise, this independent 20 hinge is quite similar to the hinge connection described with reference to Figs. 1 to 6, and does not require any further description.

It will be understood that the hinge connection whose members are integral with the parts to be 25 connected, as described with reference to Figs. 1 to 6, and the independent hinge described with reference to Fig. 7, have a wide range of usefulness. The members, including the parts with which they are integral in certain cases, are made 30 in a single operation with simple tools, for instance, dies without slides or other movable parts.

Obviously, there may be as many bearing and mating members as required with consideration of the length of the parts to be connected. Nor 35 am I limited to the particular construction shown and described.

The operation of assembling the hinge is very simple and notwithstanding the connection is very reliable. The time required for assembling 40 one of my novel hinges is but a small fraction of that required for assembling a hinge having the usual hinge pin.

I claim:

1. In a hinge connection, in combination, a 45 pair of hinge members spaced apart from one another and having bearing slots therein in axial alignment with one another and open at one end, a mating hinge member arranged to enter between the inner ends of said hinge members and having a pin thereon at each end arranged to enter said bearing slots through the open ends thereof and a resilient locking member located between said pair of hinge members and integral therewith so as to extend into the path of the 50 mating hinge member and having at its free end a seating for the mating hinge member, so that on the mating hinge member being moved into position to insert the pins thereon into the bearing slots, the resilient locking member is forced 55 back, said seating being arranged to receive the mating hinge member on the latter reaching its operative position with the pins fully home in the bearing slots, so as to permit the resilient locking member to return to its normal position and retain the mating hinge member in position.

2. In a box having a lid, a hinge connection 60 for connecting the lid to the box, comprising in combination a pair of hinge members integral with the box, said hinge members being spaced apart from one another and having bearing slots 65 therein in axial alignment with one another and open at one end, a mating hinge member integral with the lid and arranged to enter between the inner ends of said hinge members and having a pin thereon at each end arranged to enter said

bearing slots through the open ends thereof and a resilient locking member comprising an elastic tongue integral at its base with the wall of the box located between the pair of hinge members, but separated at its sides from the wall by means 5 of slots, said elastic tongue extending into the path of the mating hinge member and having at its free end a seating for the mating hinge member, so that on the mating hinge member being moved into position to insert the pins thereon into the bearing slots, the resilient locking member is forced back, said seating being arranged to receive the mating hinge member on the latter reaching its operative position with the pins fully 10 home in the bearing slots, so as to permit the resilient locking member to return to its normal position and retain the mating hinge member in position.

3. In a hinge connection, in combination, a pair of plates, one of said plates having a pair 20 of hinge members integral therewith, said hinge members being spaced apart from one another and having bearing slots therein in axial alignment with one another and open at one end, the other plate having a mating hinge member integral therewith arranged to enter between the inner ends of the pair of hinge members on the first-mentioned plate, said mating hinge member having a pin thereon at each end arranged to enter said bearing slots through the open ends 25 thereof and a resilient tongue having its base integral with the first-mentioned plate and located with its sides separated from the plate by slots between the pair of hinge members, so as to extend into the path of the mating hinge member 30 and having at its free end a seating for the mating hinge member, so that on the mating hinge member being moved into position to insert the pins thereon into the bearing slots, the resilient locking member is forced back, said seating 35 being arranged to receive the mating hinge member on the latter reaching its operative positions with the pins fully home in the bearing slots, so as to permit the resilient locking member to return to its normal position and retain the mating hinge member in position.

4. In a hinge connection, in combination, a pair of cylindrical hinge members spaced apart from one another and having bearing slots therein in axial alignment with one another and open 50 at one end, a cylindrical mating hinge member arranged to enter between the inner ends of said pair of hinge members and having a pin thereon at each end arranged to enter said bearing slots through the open ends thereof and a resilient 55 locking member located between said pair of hinge members and integral therewith so as to extend into the path of the mating hinge member and having at its free end a seating for the mating hinge member curved to the radius of 60 curvature of the mating hinge member, so that on the mating hinge member being moved into position to insert the pins thereon into the bearing slots, the resilient locking member is forced back, said seating being arranged to receive the 65 mating hinge member on the latter reaching its operative position with the pins fully home in the bearing slots, so as to permit the resilient locking member to return to its normal position and retain the mating hinge member in position.

5. In a hinge connection, in combination, a pair of hinge members spaced apart from one another and having bearing slots therein in axial alignment with one another and open at one end, a mating hinge member arranged to enter be- 70

75

5 between the inner ends of said hinge members and having a pin thereon at each end arranged to enter said bearing slots through the open ends thereof and a resilient locking member located between said pair of hinge members and integral therewith so as to extend into the path of the mating hinge member so that on the mating hinge member being moved into position to insert

the pins thereon into the bearing slots, the resilient locking member is forced back, and on the mating hinge member reaching its operative position with the pins fully home in the bearing slots the resilient locking member returns to its 5 normal position and retains the mating hinge member in position.

ALFRED BOENECKE.
